DESIGN FOR A COLLAPSIBLE UTILITY BOAT

Thomas A. Potts, Ware, and Helen V. Waskiewicz,
Warren, Mass.

Application May 10, 1946, Serial No. 129,580

Term of patent 14 years

(Cl. D71—1)

To all whom it may concern:

Be it known that we, Thomas A. Potts, a citizen of the United States, residing at Ware, in the county of Hampshire, State of Massachusetts, and Helen V. Waskiewicz, a citizen of the United States, residing at Warren, in the county of Worcester and State of Massachusetts, have jointly invented a new, original, and ornamental Design for Collapsible Utility Boat, of which the following is a specification, reference being had to the accompanying drawing, forming a part thereof.

Fig. 1 is a top plan view of a collapsible utility boat, showing our new design, and

Fig. 2 is a side elevational view thereof.

We claim:

The ornamental design for a collapsible utility boat, as shown.

THOMAS A. POTTS.
HELEN V. WASKIEWICZ.
